UNITED STATES PATENT OFFICE.

DAVID MOFFAT MYERS, OF NEW YORK, N. Y.

ANCHOR.

Application filed March 18, 1921. Serial No. 453,236.

To all whom it may concern:

Be it known that I, DAVID MOFFAT MYERS, a citizen of the United States, residing in the city, county, and State of New York, have invented certain new and useful Improvements in Anchors, of which the following is a specification.

My invention relates to anchors and is particularly concerned with anchors of the pivoted fluke type.

The primary object of the invention is to provide an anchor which is absolutely non-fouling, i. e., which cannot entangle the rope or anchor cable. To this end the invention proposes to eliminate all upstanding projections, such as the upper fluke of the ordinary anchor or the elbow in the stock thereof, about which projections the anchor cable is liable to wind itself when the vessel is riding at anchor. The invention accordingly proposes an anchor having but a single fluke pivoted at the crown and provided with means which will cause the same to "bite" quickly when the anchor is drawn along the bottom, so that a quick grip is obtained. It proposes furthermore to eliminate the elbow of the ordinary stock and to substitute therefor a chain which will lie flat on the bottom when the anchor is in use and which will permit the stock to be placed alongside the shank and effect economy of space when the anchor is stowed away.

The invention, furthermore, proposes to provide means whereby the pivotal connection between the fluke and the shank may be conveniently inspected for wear so that the user can readily ascertain the condition of this vital part of the anchor.

The above and various other objects and features of the invention will be readily understood from the following description of a specific form of embodiment thereof, reference being had to the accompanying drawings, in which—

Figure 1 is a perspective view illustrating one specific form of anchor embodying my invention;

Figures 2 and 3 show a plan view and side elevation, respectively, of the anchor of Figure 1;

Figure 4 is a view partly in section taken

along lines 4—4 in Figure 3 to illustrate a certain part thereof in detail, and

Figure 5 is a view showing an elevation of the left end of Figure 3.

55

Similar characters of reference designate similar parts in each of the several views.

The anchor illustrated in the drawings consists of a bifurcated shank composed of strips of steel 1^a and 1^b which, for part of their length, are spaced from each other by a separator 2 and a bolt 3 and which, adjacent one end, are united and secured to each other by rivets 4. A fluke 5 is pivoted on bolt 3, the crown 6 of the fluke being for this purpose provided with co-axial openings for receiving the bolt. The crown is preferably cast integral with the fluke itself, and strengthening webs 8 are provided at the base of the fluke to reinforce the junction between the fluke and the crown. A substantially V-shaped notch 9 is provided in the outer face of the crown, the depth of this notch being such that the bolt 3 passes through the notch adjacent its apex and is clearly visible when an inspection is made. The width of the crown is less than the distance between the forks of the shank so that owing to the clearance thus provided the crown may be shifted laterally and the parts of the bolt on which there is wear may be exposed and inspected. The sides of the crown terminate in forwardly projecting sharp edges 10 which will dig into the bottom when the anchor is drawn along, and thus exert a positive downward force or moment on the fluke 5 so that the same will bite quickly. A swift and positive hold will thus be obtained. It should be noted that the anchor will operate equally well with either face to the ground, the construction of the anchor being symmetrical. The edges 10 are wider than the remaining portions of the crown providing lugs 10^a which engage the forks of the shank when the fluke reaches a certain predetermined position.

This position is such as to provide the most favorable angle of entry of the fluke into the bottom when the anchor rests upon a comparatively smooth flat surface.

The fluke 5 is comparatively long and provided with a blade or palm 11 having

100

a very sharp point 12. The sides of the blade are substantially parallel at the portions marked 13. By virtue of this the palm is given a greater area or holding power without change in its sharpness or ease of penetration. It will thus be seen that because of the length of the fluke, its angle of entry and its blade area, the anchor has exceptionally large holding power and is quick to bite into the bottom. When the fluke is forced fully into the bottom the webs 8 also enter the bottom and provide additional resistance to dragging.

The stock 14 consists of a straight rod 15 having no elbow as in the usual construction, but being provided adjacent one end with a chain 15, the links of which are of such size as to pass through the hole 17 in the shank. When the anchor is to be stowed away, the stock is drawn out of hole 17 and placed lengthwise along the shank so that the chain 15 passes through hole 17 and serves to hold the stock connected to the remaining parts of the anchor, a ring 16 being provided at the end of the chain to act as a stop. When the anchor is to be made ready for use, the stock is again drawn into hole 17 until the shoulder 18 engages the shank. A key 19 is then inserted into a keyway 20 to fix the stock firmly in the shank. A chain 21 serves to secure the key to the shank.

While I have illustrated and described my invention in connection with only one preferred embodiment thereof, it will be understood that I do not intend to limit myself to the specific embodiment shown,

but that I intend to cover my invention broadly in whatever form its principle may be employed.

What I claim is:

1. An anchor comprising a shank, a stock slideable in a hole in said shank, a chain affixed to one end of said stock for passing through said hole so as to permit said stock to be laid alongside said shank, and a member associated with the end of said chain for preventing disengagement of said stock from said shank.

2. An anchor comprising a bifurcated shank, a bolt connecting the forks of said shank at their outer ends, a crown pivoted on said bolt, said crown being of less width than the distance between the forks of said shank and provided with an opening so that said bolt may be inspected for wear by shifting said crown thereon, a fluke extending from said crown and arranged to pass between the forks of said shank, said fluke having a blade provided with a portion having substantially parallel edges to provide a large holding surface having comparatively small resistance to entering the ground, and a pair of flanges extending laterally from said crown, each of said flanges being formed with an edge for engaging the ground and causing said fluke to dig in when said anchor is dragged along the ground, said flanges being of such width as to engage the said shank and limit the angle of movement of said fluke.

In testimony whereof I have affixed my signature to this specification.

DAVID MOFFAT MYERS.
